ELECTROMAGNETIC INDUCTION HEAT-TREATING APPARATUS

Howard E. Somes, Detroit, Mich., assignor, by
mesne assignments, to The Ohio Crankshaft
Company, Cleveland, Ohio, a corporation of
Ohio

Application January 11, 1945, Serial No. 572,316

17 Claims. (Cl. 219—13)

1

This invention relates to heat treating apparatus, more particularly to apparatus for heat treating circumferentially toothed articles such as gears, splines and the like, both external and internal, by induced electromagnetic heating currents.

The present invention is most importantly directed to non-progressive uniform heat treatment of such articles as are not susceptible of rotation relative to the heating coil. Although it has been possible heretofore to heat gear teeth and the like with a simple coil while providing rotation between the coil and gear, it nevertheless has been proven that due to poor coupling between the coil and the gear, longer times are required and considerable quantities of heat have to be stored up in the work-piece undergoing heat treatment in order that the roots of the teeth and the portions therebetween will reach a desired hardening temperature.

It is one of the objects of the present invention to provide an improved induction heating apparatus by means of which the hardness, the distribution of hardness and the consequent control of stresses in the tooth surfaces of circumferentially toothed articles may be accurately controlled.

Another object is to provide an induction heating apparatus utilizing a helical inducing coil wherein the coil and the article to be heated are not susceptible to rotation, means for compensating for and minimizing variations in heat application due to flux variations incident to the necessity of providing insulation between the coil turns.

Another object is to provide improved apparatus of such construction that toothed articles can be uniformly and precisely inductively heated and quenched, that is, one in which the heating will be duplicated from tooth to tooth and from gear to gear.

A further object is to provide induction heating apparatus of the foregoing character wherein means is provided to eliminate the variation of flux due to end turn configuration of the coil thus enabling the application to the gear and tooth surfaces of a uniform flux throughout the diameter of the gear and the direction of high frequency flux to and around the roots of the teeth.

With the above and other objects in view which will be apparent from the following description to those skilled in the art to which the invention appertains, the present invention consists in certain features of construction and combinations of

2

parts to be hereinafter described with reference to the accompanying drawings, and then claimed.

The foregoing objects are attained for the most part through the provision of an inducing coil having teeth which are substantially complementary to the teeth of the article to be heat treated and are arranged to register with the article teeth in predetermined spaced relation with respect thereto whereby all teeth and all corresponding tooth surfaces, including the root surfaces, are simultaneously heated to the same depth and simultaneously reach hardening temperature. In order to compensate for flux variations incident to the necessity of providing insulation between the coil turns, means is provided for rapidly reciprocating the coil relative to the article while maintaining the predetermined spacing between the teeth of the article and those of the coil. In the case of spiral teeth, means is provided for effecting a controlled oscillatory movement of the coil during this reciprocation through the provision of cooperating spirally splined guide elements such that the coil teeth move in a direction parallel to the teeth of the article being heat treated. In addition, the coil is made of such length that during reciprocation the end turns of the coil extend beyond the end faces of the article teeth and are inductively short circuited through the provision of short circuiting rings at opposite sides of the article whereby to provide for uniform flux distribution and insure the direction of high frequency flux to and around the roots of the teeth.

In the accompanying drawings which illustrate a preferred embodiment of the invention,

Figure 1 is a front elevation of the heat treating apparatus;

Figure 2 is a vertical section taken through the apparatus of Figure 1 to show the construction of various operating parts thereof;

Figure 3 is a vertical section through the lower portion of the apparatus showing the mechanism for operating a main reciprocable carriage and also showing the mechanism for actuating the support for the work-piece to be heat treated;

Figure 4 is an enlarged vertical section taken substantially on the line 4—4 of Figure 5 of the heating head shown in Figure 2;

Figure 5 is a horizontal section taken substantially on the line 5—5 of Figure 2 showing the teeth of the gear to be heat treated and the complementary teeth of the heating coil;

Figure 6 is a vertical section taken through the heating coil, the coil being removed from its supporting apparatus;

Figure 7 is a transverse section taken approximately on the line 7—7 of Figure 4;

Figure 8 is an enlarged transverse section taken substantially on the line 8—8 of Figure 2 showing the mechanism for clamping the work-piece during the heating and quenching operations;

Figure 9 is an enlarged vertical section showing the mechanism for reciprocating and oscillating the heating head, and;

Figure 10 is a section taken substantially on the line 10—10 of Figure 9 showing the means for providing adjustment of the guide means for the heating head.

Referring to the accompanying drawings in which like numerals refer to like parts throughout the several views, the heat treating apparatus of the present invention is carried by an upright supporting structure 1 having a pair of spaced, parallel, vertical guide rods 2 each of which is provided with a cylindrical piston portion 3 intermediate the ends thereof. The guide rods 2 are each provided with a bore 4 at one end having a cross passage 5 and a bore 6 at the opposite ends having a cross passage 7, the cross passages opening through the guide rods 2 closely adjacent the opposite sides of the piston portions 3 thereof.

The guide rods 2 reciprocally support a reciprocable carriage 8 having cylinder portions 9 which cooperate with the piston portions 3 and are sealed at their ends through suitable packing members 10 with the guide rods 2. Fluid under pressure admitted through the bores 4 and 6 causes the carriage to move upwardly or downwardly, depending of course upon which bore is supplied with fluid under pressure. The cylinder portions 9 are interconnected by a cross member 11 having portions 12 which surround and are keyed to the cylinder portions 9 by suitable keys 13, as shown in Figure 3. The cross member 11 is cored out to provide a chamber 14 and a central cylinder housing 15. Secured within the cylinder housing 15 by means of a clamping ring 16 and cap screws 17 is a fixed cylinder 18 within which a piston rod 19 is arranged to reciprocate, the piston rod having a piston 20 fixed thereon which cooperates with the cylinder 18, the opposite ends of the cylinder being sealed through suitable packing elements 21 with the piston rod 19. The piston rod 19 is raised by admitting fluid under pressure through conduit 22 to the lower side of the piston 20 and is lowered by admitting fluid under pressure through conduit 23 to the upper side of the piston 20. In order to cushion the piston rod 19 as it nears the ends of its upward and downward strokes, the tubular packing elements 21 are enlarged at their inner ends as indicated at 24, to slidably receive cylindrical portions 25 of the piston 20. Adjacent the portions 24 are conduits 26 which are of restricted size and function when the cylindrical portions 25 engage with the portions 24 to slow down the piston rod and thereby provide a fluid cushion.

The upper end of the piston rod 19 is provided with a flange 27 to which a tubular housing 28 is secured by cap screws 29, this housing contains mechanism for clamping and supporting the work-piece to be heat treated. The work-piece selected for illustration is a gear 30 having spiral external teeth and having a bore 31.

The work clamping mechanism (Figures 2 and 8) includes a recessed base 32 arranged within the housing 28 and within which a vertical rod 33 having a squared upper end, is provided for

vertical movement. The lower end of the rod 33 is provided with a portion 34 which is threaded in a tubular element 35 arranged within a casing portion 36. The casing portion 36 is carried by an annular member 37 within the housing 28 and is provided with a spring 38 which engages a flange portion of the tubular member 35, the spring 38 urging the rod 33 to an uppermost position. The lower end of the tubular portion 35 projects beyond the portion 36 and is provided with an element 39 fixed thereto and having pin 40 which is engaged within a recess in the member 36 to hold the member 35 against rotation. Rotatably carried on the rod 33 between a shouldered portion 33a and a fixed nut 33b is a cylindrical member 41 having spaced shoulder portions 41a. Arranged about the rod 33 and pivotally supported on pins 43 are three bell crank levers 42, each bell crank lever having on one leg thereof a pivoted block 42a disposed between the two shoulder portions 41a. The other leg of each bell crank lever 42 has a pivoted connection through pin 44 with a radially slidable clamping member 45 guided by guideways formed in the base 32. Each of the clamping elements 45 is provided with an upstanding portion 46 surrounding the rod 33. By forcing the rod 33 downwardly the shoulder portions 41a cause the clamping members 45 to move radially inwardly whereby the bore of the gear 30 may be disposed in surrounding relation with respect to the upstanding portions 46. Upon release of the downward pressure, the spring 38 causes upward movement of the rod 33 whereby the shoulder portions 41a through the bell crank levers 42 move the clamping members 45 radially outwardly into clamping engagement with the bore 31 of the gear 30. Adjustment of the clamping members 45 is provided through rotation of the rod 33 in the tubular member 35.

Positioned upon the housing 28 (Figure 4) is an annular ring 47 and an annular element 48 which cooperate through screws 49 to clamp an annular element 50 composed of a plurality of laminations of a metal having high magnetic permeability in position. The annular element 50 is provided with a circumferential recess which houses a pair of axially aligned short circuiting rings 51 insulated from each other and from the annular element 50.

The heating head as shown in Figures 2, 4, 5 and 6 embodies a helical coil 52 of hollow formation and having internal teeth 53 which teeth have substantially the same contour and spiral angle as the teeth of the gear to be heat treated. This helical coil forms a subject matter of and is claimed in my co-pending application, Serial No. 572,318 filed Jan. 11, 1945, now Patent No. 2,435,242 issued February 3, 1948.

The coil 52 is provided with a continuous internal cooling passage 54 and is supported within a recess provided in an annular radially laminated member 55 of high magnetic permeability. This member is arranged within an annular ring 56 having annular end clamping plates 57 secured thereto by screws 58 which securely hold the member 55 in position. The heating head is supported through the upper clamping plate 57 from a tubular housing 59 having a fixed piston 60 intermediate the ends thereof. Surrounding the piston 60 in cooperative relation therewith is a cylinder 61 which in turn is supported within a cross member 62 which is rigidly mounted on the guide rods 2. The opposite ends of the cylinder 61 are sealed by suitable packing elements 63 having

slidable bearing engagement with the member 59. Fluid under pressure is admitted through conduits 64 to the opposite ends of the cylinder 61 to provide for rapid reciprocation of the member 59 for a purpose to be subsequently described.

Arranged within the tubular member 59 is an arbor 65 comprised of inner and outer concentric tubular conductors 66 and 67 respectively insulated from each other by an insulating sleeve 68. The upper end of the arbor is suitably supported by the supporting structure 1 well above the cross member 62. As shown in Figures 2 and 4 the inner conductor extends downwardly beyond the outer conductor. The tubular member 59 carries an outer annular ring 69 which is provided with an annular conducting ring 70 having a plurality of circumferentially spaced spring contact fingers 71 surrounding and slidably engaged with the outer conductor 67. Arranged within the annular conducting ring 69 is an inner annular conducting ring 72 having a plurality of circumferentially spaced spring contact fingers 73 surrounding and slidably engaged with the extending end of the inner conductor 66, the inner conducting ring 72 having an annular passage 74 therein. The inner and outer conducting rings 72 and 69 respectively are insulated from each other by suitable insulation 75 and are held in place within the member 59 by a clamping plate 76 suitably secured to the member 59. The conducting rings 72 and 69 are electrically connected with the ends of the helical coil 52 through horizontal inner and outer concentric conducting elements 77 and 78 respectively which are insulated from each other and are connected with vertical inner and outer concentric conductor elements 79 and 80 which are insulated from each other. The upper end of the helical coil 52 is connected through a conducting element 81 which is connected with the inner conducting element 79 and is insulated from the outer conducting element 80 and the annular casing 56 as shown in Figure 2. The lower end of the helical coil 52 is connected by a conducting element 82 through a vertical rod 83 which is clamped within the outer conducting element 80 in electrical engagement therewith. The horizontal conducting element 77, the vertical conducting element 79 and the conducting element 81 are provided with interconnecting passages 84. The passage of the element 81 connects with the passage 54 of the coil 52 and the passage of the horizontal conductor 77 connects with the annular passage 74 of the inner conducting ring 72. The lower conducting element 82 is provided with a passage 85 which connects with the lower end of the coil passage 54 and is provided with a connecting conduit 86. Extending through the member 59 and insulated therefrom is a tubular member 87 having threaded connection with the inner conducting ring 72 and a passageway 88 connecting with the passage 74 of the inner conducting ring 72. A conduit 89 is connected with the passageway 88. Suitable cooling fluid is fed through the conduit 89 from whence it travels through passages 88, 74 and 84 and thence through the coil passage 54 and discharges through the passageway 85 of the conducting element 82 and the conduit 86 to cool the coil 52. Threadably secured within the extending end of the inner conductor 66 is a sleeve 90 which supports a tubular member 91. The tubular member 91 is insulated from the sleeve 90. Secured by means of a nut 92 to the lower end of the member 91 is an annular plate 93 having an annular sleeve 94 thereon and a plate 95 sup-

ported on the sleeve 94. Surrounding the sleeve 94 and clamped between the plates 93 and 95 is an annular laminated member 96 of high magnetic permeability which supports a pair of axially aligned hollow short circuiting rings 97, the rings 97 being insulated from each other.

Extending downwardly through the inner conductor is a conduit 98 which is threadably connected with the bore of the member 91, the portion of the bore of the member 91 with which the conduit 98 is connected being of reduced diameter as indicated at 99. The conduit 98 above its connection with the bore is circumferentially spaced from the bore to provide an annular passage 100 which connects with the bore 101 of the inner conductor 66. The plate 93 is provided with a pin 102 threaded into a member 103 which carries a pin 104 threaded into the upper short circuiting ring 97, the member 103 being also provided with a pin 105 threaded into the lower conductor ring 97. The pins 102, 104 and 105 are provided with passages 106, passages of the pins 104 and 105 being interconnected by a passage 107 in the member 103, and the passage in the pin 102 being interconnected with the bore 99 through a passage 108 formed in the plate 93 and the tubular member 91. A similar arrangement is provided diametrically opposite the pin members just described to provide a passage 109 from the upper short circuiting rings 97 through the plate 93 and thence through the wall of the tubular member 91 into connection with the circumferential space 100. The space within the lower short circuiting ring 97 is connected with the passage 109 through a passage 110. Cooling fluid is circulated through the bore 101 of the inner conductor 66 and travels through the circumferential space 100, where it flows through passages 109 and 110 to the interior of the short circuiting rings 97 to maintain the same cool and discharges therefrom through the passages 106, 107 and 108 to the bore 99 of the member 91 where it discharges through the conduit 98 (Figure 7).

Assuming the gear 30 to be in the position shown in Figure 2, the coil 52 is reciprocated through the reciprocable tubular member 59 at a relatively high speed to eliminate the variations in heat application which result from the flux variations which are due to the necessity of providing insulation between the turns in the coil 52. The stroke of the tubular member 59 is relatively short. Inasmuch as the gear shown for illustration is of the spiral type, the teeth of the coil 52 are caused during reciprocation to parallel the teeth of the gear by means of a spiral guide element 111 carried by the upper end of the reciprocable member 59 and having guide portions in slidable engagement with spiral splines 112 which are formed on a sleeve member 113, the sleeve member 113 being held in fixed position by a housing 114 secured by screws 115 to the cross member 62.

By loosening the nut 116 which holds the guide sleeve 113 in fixed position and by loosening the nut 117 which holds the guide element 111 in fixed position and then by adjusting the screws 118 the guide element 111 and the guide sleeve 113 may be rotated together a slight amount, to rotate the heating head a predetermined amount for accurate alignment of the teeth of the coil 52 so as to provide for proper spacing of the teeth of the coil with the teeth of the gear 30. Also, guide element 111 and guide sleeve 113 are removable for replacement by other guide

elements and sleeves in which the teeth have a different spiral angle to correspond with the teeth of the particular gear to be heat treated. In case the gear should happen to be a spur gear then, of course, the interengaging splines of the guide element and guide sleeve are of the spur type to correspond with the teeth of the gear.

As shown in Figure 4, the lowermost of the upper short circuiting rings 97 is provided with spiral teeth 119 and the uppermost of the lower short circuiting rings 51 is provided with spiral teeth 120, the teeth 119 and 120 being complementary to the teeth of the coil 52.

In the operation of the apparatus, the gear 30 is moved upwardly into initial registration with the teeth of the coil 52 and in order to provide for this registration since the teeth of the gear and the coil, it is necessary to effect a rotation of the gear during this movement. In order to provide for this rotation and proper registration, the lower end of the piston rod 19 which projects beyond the cylinder 18 is provided with a spirally splined element 121, the splines of which register with corresponding splines of a guide sleeve 122. The guide sleeve 122 is held in fixed position by a suitable clamping plate 123 which is secured to a portion 124 of the supporting structure 1. The splined element 121 fits within the end of the piston rod 19 and is removably secured thereto by a threaded collar 125 and is held against relative rotation by a key 126. The splined element 121 and the guide sleeve 122 as in the case of the guide element 111 and sleeve 113 are interchangeable with other guide elements and sleeves having interengaging splines of the same spiral angle as the teeth of the gear to be heat treated. Obviously, during upward movement of the piston rod 19 the guide element 121 and guide sleeve 122 cause the gear 30 to rotate the desired amount whereby to register teeth 30 thereof and the teeth 120 of the lower short circuiting rings 51 with the teeth of the coil 52.

The quenching mechanism which forms the subject matter of my co-pending application Serial No. 572,315 filed Jan. 11, 1945 is carried by the cross member 11 of the carriage 8. This mechanism comprises a manifold 127 secured to the cross member 11 and having spaced inner and outer annular elements 128 and 129 secured thereto. Clamped between the upper ends of these elements is an annular quench distributing ring 130 having spiral teeth corresponding to the teeth of the gear to be heat treated. The quench ring 130 is removably secured to these elements by a clamping ring 131 to provide for interchange with other quenching rings in which the teeth thereof correspond to the teeth of the particular gear to be heat treated. Quenching fluid under pressure is introduced into the manifold 127 through conduits 132 and the quenching fluid flows upwardly through the space between the annular elements 128 and 129 and is discharged through elongated orifices 133 in the ring 130 to direct quenching fluid against the heated surfaces of each tooth of the gear 30.

As shown in Figure 3 the teeth of the gear 30 when the piston rod 19 is in its lowermost position, are registered with the teeth of the quenching ring 130. In the operation of the apparatus described, the carriage 8 initially is in its lowermost position, that is the carriage is downwardly positioned with respect to the uppermost position shown in Figure 1 and, in this position, the piston rod 19 is in its lowermost

position whereby to provide a space between the gear clamping mechanism and the heating head for removal and positioning of a gear for heat treatment. Assuming the elements to be in these positions, the gear 30 is first disposed about the rod 33 and the rod 33 is moved downwardly to permit the upstanding portions 46 of the clamping mechanism to be disposed within the bore 31 of the gear 30. Upon release of the downward pressure on the rod 33, the spring 38 moves the rod 33 upwardly thus causing the clamping jaws 45 to move radially outwardly to securely engage the bore 31 of the gear and thereby hold the gear in predetermined fixed position and axially centered with respect to the heating head and the quenching ring 130. Suitable gear locating pins 134 may be utilized to cooperate with and additionally locate the gear in its proper position.

20 The carriage is then moved upwardly through suitable control mechanism (not shown) which controls the flow of actuating fluid to the cylinders 9 of the carriage to effect this movement. The uppermost position of the carriage is shown in Figure 2, suitable stops 135 being provided on the guide rods 2 to predetermine this position. Fluid under pressure is then admitted by the control mechanism into the cylinder 18 to cause the piston rod 19 to move upwardly to its 25 uppermost position, during which movement as previously described, the gear is rotated to register the teeth thereof and the teeth of the lowermost short circuiting ring 51 with the teeth 53 of the coil 52.

30 Fluid under pressure is then admitted to the cylinder 61 through first one and then the other of the conduits 64 by means of suitable control mechanism (not shown) to cause the tubular member 59 to reciprocate at a relatively high speed. During this reciprocation the guide element 111 and the guide sleeve 112 cause the teeth of the coil 52 to oscillate and have reciprocal movement parallel to the teeth of the gear. At the time the coil 52 is started to reciprocate as 35 just described, the coil 52 is energized from a source of high frequency current such as from a suitable transformer of the type shown in my co-pending application Serial No. 538,975 filed June 6, 1944 now Patent No. 2,420,449 issued May 13, 1947. The coil 52 is thus provided with a 40 small amount of circumferential oscillatory movement which is but a small part of a revolution and is dependent on the helix angle for the length of stroke whereby to eliminate variations in the 45 heating of the surfaces of the gear teeth due to the flux variations arising out of the necessity of providing insulation between the turns of the coil.

50 It will be noted that the coil 52 is of greater length than the width of the gear face and that the end turns of the coil are projected over the short circuiting rings 51 and 97 in such manner that at each end of the short stroke of the coil 52, the end turns will be in surrounding relation 55 with respect to at least one of the short circuiting rings 51 at the lower limit. This short circuiting arrangement provides an effective means through inductive short circuiting of the end turns of the coil for eliminating the variations of flux due to the end turn configuration of the coil, thus enabling the application to the gear face and teeth thereof of a uniform flux throughout the diameter of the gear.

55 After the faces of the gear teeth have been accurately heated to hardening temperature the

control mechanism, after such suitable time delay as is deemed necessary, causes the piston rod 19 to move downwardly to its lowermost position thus bringing the teeth of the gear into registration with the teeth of the quenching ring 130 at which time the quenching fluid is admitted through the conduits 132. The quenching fluid after quenching the heated faces flows downwardly within the inner element 128 and thence through openings 136 into the chamber 14 of the cross member 11 where it discharges through a suitable conduit 137.

It is to be borne in mind that the arbor 65 is stationary and the tubular member 59 and spring conducting fingers 71 and 73 reciprocate relative to the arbor. A suitable collar 140 fixed within member 59 provides means for maintaining the arbor 65 and member 59 in axial alignment.

After the quenching operation the gear is then removed and replaced with another gear to be heat treated through repetition of the cycle just described.

While I have described the treatment of a helical type gear it will be obvious that the apparatus described can be satisfactorily used for the heat treatment of spur gears, splines and other circumferentially toothed members. The term "gear" as used in the claims is to be construed to mean any circumferentially toothed article.

While the teeth of the coil 52 are shown to have the same contour as the teeth of the gear selected for illustration, the coil teeth may be varied somewhat to obtain a desired predetermined heating effect. Also, the coil teeth may be varied to provide for hardening the tooth sections only, leaving the root sections unhardened and in other cases to provide for massive heat treatment for wear resistance and high strength. It is to be understood also that the principles herein disclosed are applicable to the treatment of internally toothed or splined structures.

While I have not shown the control mechanism and circuits for the various parts, it is to be understood that the same may be of any desired type to bring about the operations described.

It will be obvious that various changes may be made in the detailed construction and arrangement of the parts described without departing from the spirit and substance of the invention, the scope of which is defined by the appended claims.

What is claimed is:

1. In an apparatus for heating circumferentially toothed workpieces by electromagnetic induction heating, a support for rigidly holding the toothed workpiece to be heated, an energizable helical inducing coil having circumferential teeth corresponding in number and spacing to the teeth of the workpiece, the teeth of one of the coil and workpiece being external and the teeth of the other being internal, means for effecting relative axial movement between said support and the workpiece to register the teeth of said workpiece and the coil with each tooth of the workpiece disposed between and spaced from a pair of adjacent teeth of said coil, and means for effecting rapid relative reciprocatory movement between the teeth of the workpiece and coil while in registration and during energization of said coil.

2. In an apparatus for heating circumferentially toothed workpieces by electromagnetic induction heating, a support for rigidly holding the toothed workpiece to be heated, an energiz-

able helical inducing coil having circumferential teeth corresponding in number and spacing to the teeth of the workpiece, the teeth of one of the coil and workpiece being external and the teeth of the other being internal, means for effecting relative axial movement between said support and the workpiece to register the teeth of said workpiece and the coil with each tooth of the workpiece disposed between and spaced from a pair of adjacent teeth of said coil, and means for effecting rapid relative reciprocatory movement between the teeth of the workpiece and coil while in registration and during energization of said coil, together with means for maintaining the spacing between the teeth of the workpiece and said coil constant during said relative reciprocatory movement.

3. In an apparatus for heating circumferentially toothed workpieces by electromagnetic induction heating, a support for rigidly holding the toothed workpiece to be heated, an energizable helical inducing coil having circumferential teeth corresponding in number and spacing to the teeth of the workpiece, the teeth of one of the coil and workpiece being external and the teeth of the other being internal, means for effecting relative axial movement between said support and the workpiece to register the teeth of said workpiece and the coil with each tooth of the workpiece disposed between and spaced from a pair of adjacent teeth of said coil, and means for effecting rapid relative reciprocatory movement between the teeth of the workpiece and coil while in registration and during energization of said coil, the axial width of said coil being greater than the axial width of the tooth faces of the workpiece and the stroke of said reciprocatory movement being such as to maintain the workpiece within the axial limits of said coil during said reciprocatory movement.

4. In an apparatus for heating circumferentially toothed workpieces by electromagnetic induction heating, a support for rigidly holding the toothed workpiece to be heated, an energizable helical inducing coil having circumferential teeth corresponding in number and spacing but of lesser thickness than the teeth of the workpiece, the length of the teeth of said coil being greater than the length of the teeth of the workpiece, the teeth of one of the coil and workpiece being external and the teeth of the other being internal, a support for rigidly holding said coil, said supports maintaining the workpiece and said coil in axial alignment, means for axially moving one of said supports toward the other support to register the teeth of the workpiece and said coil with each tooth of one spaced from adjacent teeth of the other, means for rapidly reciprocating said other support, the reciprocable stroke thereof being of such length that the workpiece teeth are maintained within the confines of the length of the teeth of said coil, and means for constraining the teeth of the workpiece and said coil to parallel relationship during the reciprocating movement.

5. In an apparatus for heating circumferentially toothed workpieces by electromagnetic induction heating, a support for rigidly holding the toothed workpiece to be heated, an energizable helical inducing coil having circumferential teeth corresponding in number and spacing but of lesser thickness than the teeth of the workpiece, the length of the teeth of said coil being greater than the length of the teeth of the workpiece, the teeth of one of the coil and workpiece being

external and the teeth of the other being internal, a support for rigidly holding said coil, said supports maintaining the workpiece and said coil in axial alignment, means for axially moving one of said supports toward the other support to register the teeth of the workpiece and said coil with each tooth of one spaced from adjacent teeth of the other, means for rapidly reciprocating said other support, the reciprocable stroke thereof being of such length that the workpiece teeth are maintained within the confines of the length of the teeth of said coil, a supporting structure for said other support, and cooperable guide elements on said supporting structure having interfitting circumferential portions, said interfitting portions being parallel to the teeth of the workpiece and said coil for maintaining the spacing between said teeth during the reciprocating movement.

6. In an apparatus for heating the teeth of spiral gears by electromagnetic induction heating, a helical induction heating coil having spiral teeth corresponding in number, spacing and spiral angle to the teeth of the gear, the teeth of one of the coil and gear being external and the teeth of the other being internal, the teeth of said coil being of greater length than the teeth of the gear, and the teeth of the gear and coil being registerable with each other with each tooth of one spaced from adjacent teeth of the other, a support for said coil, a support for the gear, and means for effecting rapid combined oscillatory and reciprocable movement of one of said supports for oscillating and reciprocating one of said gear and coil relative to the other while said teeth are in registration.

7. In an apparatus for heating the teeth of spiral gears by electromagnetic induction heating, a helical induction heating coil having spiral teeth corresponding in number, spacing and spiral angle to the teeth of the gear, the teeth of one of the gear and coil being external and the teeth of the other being internal, the teeth of the coil being of greater length than the teeth of the gear, a support for the gear coaxial therewith; a support for said coil coaxial therewith, said supports being axially aligned with each other, separate guide means for guiding each of said supports for axial movement, cooperable interengaged splined elements carried by each support and its associated guide means and having spiral splines of the same spiral angle as said teeth for rotatively guiding said supports during axial movement thereof, actuating means for moving one of said supports axially toward the other to effect registration of the teeth of the gear and said coil with the teeth of each spaced from the teeth of the other, and means for rapidly reciprocating the other of said supports whereby to relatively reciprocate and oscillate the teeth of the gear and said coil, the reciprocable stroke thereof being such that the teeth of the gear are maintained within the confines of the teeth of said coil during said reciprocation.

8. In an apparatus for heating metallic articles by electromagnetic induction heating, an energizable helical inducing coil of greater axial width than the surface of the article to be heated, means for supporting the article adjacent and within the axial limits of said coil, and short circuiting rings at opposite sides of the article so supported and adjacent said coil in spaced relation therewith, said rings extending beyond the axial limits of said coil for inductively short circuiting the end turns of said coil during ener-

gization thereof, said coil having at the side opposite said rings an element of high magnetic permeability and said rings having at the sides opposite said coil elements of high magnetic permeability.

9. In an induction heating apparatus, an induction heating coil, a short circuiting ring concentrically disposed in spaced relation with an end of said coil, concentric supports for said coil and said ring, the support for said ring including concentric electric conductors insulated from each other and said ring, one of said conductors extending axially beyond the other, the support for said coil having contactors insulated from each other, respectively, electrically connected with the ends of said coil and slidably engaged with the ends of said conductors, and means for reciprocating one of said supports relative to the other to effect relative reciprocation between said coil and ring.

10. In an apparatus for heating the surfaces of the teeth of spiral gears, a helical inducing coil having teeth corresponding in number, spacing and spiral angle with, but of lesser thickness than the teeth of the gear to be heated, a support for said coil, a support for holding the gear in axial alignment with said coil and in normally axially spaced relation therewith, supporting structures for said supports, means for axially moving one of the supports toward and away from the other, and cooperable elements carried by said one support and its supporting structure and having interengaged splines of the same spiral angle as said teeth for rotatively guiding the teeth of the gear and coil into and out of spaced registration during the respective movements of said one support toward and away from the other support.

11. In an apparatus for heating the surfaces of the teeth of spiral gears, a helical inducing coil having teeth corresponding in number, spacing and spiral angle with, but of lesser thickness than the teeth of the gear to be heated, a support for said coil, a support for holding the gear in axial alignment with said coil and in normally axially spaced relation therewith, supporting structures for said supports, means for axially moving one of the supports toward and away from the other, cooperable elements carried by said one support and its supporting structure and having interengaged splines of the same spiral angle as said teeth for rotatively guiding the teeth of the gear and coil into and out of spaced registration during the respective movements of said one support toward and away from the other support, and means rotatively adjusting said cooperable elements relative to said one support and its supporting structure.

12. In an apparatus for surface heating a toothed gear workpiece by electromagnetic induction heating, an energizable helical induction heating coil having its turns axially spaced apart and having teeth matching the teeth of said workpiece, one of said coil and workpiece having an external surface and the other having an internal surface and the axial width of said coil being materially greater than the axial width of the workpiece surface to be heated, means for relatively moving said coil and the workpiece to position said external and internal surfaces and teeth in adjacent operative heating relation with the toothed surface of the workpiece within the axial limits of the toothed portion of said coil, and means operative during energization of said coil and while the teeth of the workpiece and coil

are intermeshed for effecting rapid relative reciprocatory movements between said coil and the workpiece while keeping the circumferential relationship of the teeth of the workpiece and coil constant, the reciprocatory stroke being such that the workpiece with its teeth is maintained within said axial limits of the teeth of said coil during said reciprocatory movements.

13. In an apparatus for surface heating a toothed gear workpiece by electromagnetic induction heating, an energizable helical induction heating coil having its turns axially spaced apart and having teeth matching the teeth of said workpiece, one of said coil and workpiece having an external surface and the other having an internal surface, means for relatively moving said coil and the workpiece to position said external and internal surfaces and teeth in adjacent operative heating relation, the one within the other, said coil being of such axial width that in said operative heating relation the end turns thereof are disposed axially beyond the axial limits of the workpiece surface to be heated, and means for effecting repeated rapid reciprocatory movements between said coil and workpiece while maintaining the teeth of the workpiece and coil intermeshed and at constant spacing within the axial limits of said coil during energization of said coil.

14. In an apparatus for surface heating a toothed gear workpiece by electromagnetic induction heating, an energizable helical induction heating coil having its turns axially spaced apart and having teeth matching the teeth of said workpiece, one of said coil and workpiece having an external surface and the other having an internal surface, means for relatively moving said coil and the workpiece to position said external and internal surfaces and teeth in adjacent operative heating relation, the one within the other, said coil being of such axial width that in said operative heating relation the end turns thereof are disposed axially beyond the axial limits of the workpiece surface to be heated, inductive short circuiting rings at opposite sides of the surface of the workpiece to be heated and in spaced overlapping relation with said end turns of said coil, and means for effecting repeated rapid relative reciprocatory movements between said coil and the workpiece of such minimum stroke that said end turns and short circuiting rings are maintained in overlapping relation during said movements.

15. In an apparatus for heating the circumferential surface of a workpiece by electromagnetic induction heating, a support for holding the workpiece to be heated, an energizable inducing coil having a length greater than the length of said workpiece, a support for said coil coaxial with said workpiece support, power means for axially moving one of said workpiece and coil

supports until the workpiece is within the axial limits of the length of said coil, and other power means for reciprocating one of said workpiece and coil supports rapidly while maintaining the workpiece within the limits of length of said coil.

- 5 16. In an apparatus for heating the circumferential surface of a workpiece by electromagnetic induction heating, a support for holding the workpiece to be heated, an energizable inducing coil having a length greater than the length of said workpiece, a support for said coil coaxial with said workpiece support, power means for axially moving one of said workpiece and coil supports until the workpiece is within the axial 10 limits of the length of said coil, and other power means for reciprocating one of said workpiece and coil supports rapidly while maintaining the workpiece within the limits of length of said coil, said workpiece and coil having mating teeth, and 15 interacting means associated with said supports and power means for bringing the teeth of the workpiece and coil into spaced meshing relationship for heating and so maintaining them during the reciprocatory movement.
- 20 17. In an apparatus for heating the circumferential surface of a workpiece by electromagnetic induction heating, a support for holding the workpiece to be heated, an energizable inducing coil having a length greater than the length of said workpiece, a support for said coil coaxial with said workpiece support, power means for axially moving one of said workpiece and coil supports until the workpiece is within the axial 25 limits of the length of said coil, and other power means for reciprocating one of said workpiece and coil supports rapidly while maintaining the workpiece within the limits of length of said coil, said workpiece and coil having mating helical teeth, and interacting means between said supports and power means for bringing the spiral teeth of the workpiece and coil into spaced meshing relationship for heating and so maintaining them during the reciprocatory movement.

HOWARD E. SOMES.
